WIRE TWISTING PLIER

Filed March 19, 1943

INVENTOR.

James T. Stinson

I claim:

1. A wire twisting device of the character described, comprising a body member, a pair of plierlike members pivotally connected together and mounted supportedly at their place of connection on said body member, a normally open split spring beak assembly mounted rotatably on said body member about an axis substantially parallel with the axis of the pivotal mounting of said plierlike members and in cooperative relation to said members to be thereby moved into closed gripping engagement with a wire ligature in its utilitarian application, a manually operable shaft having an end portion mounted rotatably on said body member about an axis substantially at right angles to the axis of said rotatable beak assembly, and a geared driving connection between said shaft and said beak assembly.

2. A wire twisting device of the character described, comprising a plierlike instrument which includes a body member insertable freely in oral and other cavernous areas of the human body, angularly disposed, normally open, cooperatively opposed beak members mounted rotatably on said body member, a manually operable, lever-armed, plier-type, clamping element pivotally mounted on said body member for closing said beak members in gripping engagement with a wire ligature that is to be twisted in its utilitarian application, and an angularly disposed rotatable operating shaft for imparting rotation to said beak members.

3. A wire twisting device of the character described, comprising a plierlike instrument which includes a body member insertable freely in oral and other cavernous areas of the human body, cooperatively opposed, hinged beak members mounted rotatably on said body member and extending laterally therefrom, yieldable means for holding said beak members normally in open

relation to each other and returning them to such position, a pair of elongated clamping members mounted pivotally on said body member and co-operatively engageable at one end with said beak members to effect closing of the latter in gripping engagement with a wire ligature that is to be twisted in its utilitarian application, the opposite end portions of said clamping members being turned and extended at an angle from the adjacent place of pivotal mounting on the body member and provided with hand-grasp portions for effective manipulation of said clamping members, and a manually operable shaft mounted rotatably on said body member and having a driving connection with said beak members whereby to effect rotation of the latter, said shaft being elongated and extending in angular relation adjacent to and beyond said angularly extended manipulating end portions of said clamping members.

4. A surgical wire twisting device of the character described, comprising cooperative rotatable beak members insertable in oral and other cavernous areas of the human body and arranged and adapted for gripping a wire ligature that is to be twisted in its utilitarian application, angularly disposed, plier-like, members hingedly mounted on a common supporting body with said beak members, adjacent end portions of said plier-like members cooperatively engaging said beak members laterally and oppositely thereof for clamping said beak members in gripping contact with the wire ligature, and an elongated angularly disposed, manually operable, rotatable shaft having an angular driving connection at one end with said beak members for effecting rotation of the latter, said shaft having provision at its opposite end for positive manipulable rotation of said shaft.

JAMIE THOMPSON STINSON.
